(No Model.)

J. M. DUNCAN.
FURNACE GRATE.

No. 321,890.

Patented July 7, 1885.

UNITED STATES PATENT OFFICE.

JOSEPH M. DUNCAN, OF WARSAW, NEW YORK, ASSIGNOR TO HIMSELF
AND EBEN O. MCNAIR, OF SAME PLACE.

FURNACE-GRAVE.

SPECIFICATION forming part of Letters Patent No. 321,890, dated July 7, 1885.

Application filed March 16, 1885. (No model.)

To all whom it may concern:

Be it known that I, JOSEPH M. DUNCAN, of Warsaw, in the county of Wyoming and State of New York, have invented a new and useful Improvement in Furnace-Grates; and I do hereby declare that the following is a full and exact description of the same, reference being had to the accompanying drawings, and to the letters of reference marked thereon.

10 My invention relates to improvements in grates for furnaces; and its object is to render the same self-feeding and self-discharging for the purpose of saving labor as well as giving better combustion. It is well known that the frequent opening of furnace-doors for feeding and raking purposes admits a large amount of cold air to the surface of the fire, which deadens the same, besides injuring the combustion, and in furnaces fed by hand they necessarily have 15 to be raked out at least once every six hours, which cools the walls and lessens the amount of evaporation. With my improvements these causes and objections are removed, and a clean fire is constantly maintained with much less 20 or comparatively no labor.

The novelty of these improvements consists in a revolving or otherwise traveling grate, combined with conveyers arranged at the rear and front ends of the furnace; and it further 25 consists in means for supporting and operating the same, together with other details of construction and arrangement, all as more fully hereinafter described, and set forth in the claims.

30 For the better understanding of my improved devices, together with their mode of application to a furnace, attention is invited to the accompanying drawings, in which—

Figure 1 is a transverse section of a furnace 35 provided with grate and conveyers constructed and arranged in accordance with my invention; Fig. 2, a similar view of a modification; Fig. 3, a side elevation, partly broken away, of the furnace shown in Fig. 1; Fig. 4, a detail of a section of the grate.

Like letters of reference denote corresponding parts in the views.

A denotes an ordinary furnace with a door, B, at its front end, and a bridge-wall, C, at its 40 rear end. Three or more pairs of sprocket-

wheels, D D, are arranged in the interior, next to the side walls of the furnace, upon shafts a, running in the same plane parallel to each other and having bearings in said side walls. These wheels carry a pair of endless chain-belts or sprocket-chains, D' D', to which are secured the ends of a series of transverse perforated bars, b b, made from cast or wrought iron, with either a flat or corrugated upper surface, and these bars, together with the chains 55 D' D', constitute the grate proper. The shafts a extend through the sides of the furnace, and are provided on their outer ends with additional sprocket-wheels, E E, and an endless-chain belt or sprocket-chain, E', for each set 60 of said wheels, whereby the strain is evenly distributed on all the shafts and wheels. One of the shafts a is farther extended at one end, and has any suitable wheel or pulley, with appropriate connections with the driving-power. 65 The grate-surface proper is level, or nearly so, and on the revolution of the driving-shaft the chains, together with the grate, travel from the rear toward the front of the furnace. All 70 coal is fed upon the revolving grate in the rear 75 of the bridge-wall C by means of a conveyer, represented at F, which should be so arranged as to supply the grate uniformly at a speed relative to that of the grate. This conveyer is covered and protected from the heat by the 80 bridge-wall, over which the flames pass without affecting the fresh coal, except when such coal shall have been carried out from under the bridge-wall. The driving-power should be under such control as to regulate the speed 85 of the grate, to the end that the coal shall have been consumed by the time it reaches the shaft a at the front of the furnace, where it is dumped and deposited in a conveyer or receiver, F', 90 similar to the one at the rear end under the bridge-wall of the furnace.

In a furnace with no bridge-wall, or when it is desirable, the grate (by the use of extra sprocket-wheels D' D', arranged as shown in Fig. 2) may be made to rise on a gentle incline 95 upward on its return to the point where it commences to travel on a level. With this change the conveyer for feeding the coal is arranged below the level of the grate proper, and this, then, allows a free passage of the smoke and 100

heat back to the chimney and return-flue. The angles of the revolving grate, as well as the size of the same, may be altered under certain circumstances.

5. By my improved grate the fresh coal is constantly being carried into the hottest of the fire, and is entirely consumed by the time it reaches the front of the furnace, thus maintaining a fresh clean fire at all times without raking the same or opening the furnace-doors; and it will be seen that this grate, with its supporting and carrying devices, is protected from the heat by the cold air which enters from the draft-openings at the front, and they are thereby rendered more durable.

Having thus described my invention, what I claim, and desire to secure by Letters Patent, is—

1. The combination, in a furnace, of a traveling grate, a conveyer for feeding the coal, and a conveyer for receiving the ashes, substantially as described.

2. The combination, in a furnace, of a traveling grate, and a conveyer for receiving the ashes at the front end, substantially as described.

3. The combination, in a furnace, of a trav-

eling grate, a conveyer for feeding coal from the rear of the fire, and a conveyer for receiving the ashes at the front end, substantially as described.

4. The combination, with a furnace, of a traveling grate arranged to carry the fuel upward on an incline from the rear of the fire, and thence on a level to the front of the furnace, substantially as and for the purposes set forth.

5. The combination, in a furnace, of a traveling grate moving on an incline and on a level, and a conveyer for feeding the coal, arranged below the top level of said grate, substantially as described.

6. The combination, in a furnace, of a set of sprocket wheels and chains, a series of perforated grate-bars secured to said chains, and another set of sprocket wheels and chains on the outside of the furnace, substantially as and for the purposes set forth.

In testimony whereof I affix my signature in presence of two witnesses.

JOSEPH M. DUNCAN.

Witnesses:

E. O. MCNAIR,
WM. H. McCONNELL.
